UNITED STATES PATENT OFFICE.

CHESTER M. ROE, OF JERSEY CITY, NEW JERSEY.

SWITCH-INDICATOR.

1,088,454.

Specification of Letters Patent.

Patented Feb. 24, 1914.

Application filed November 25, 1911. Serial No. 662,339.

To all whom it may concern:

Be it known that I, CHESTER M. ROE, a citizen of the United States, and a resident of Jersey City, in the county of Hudson and State of New Jersey, have invented a new and Improved Switch-Indicator, of which the following is a full, clear, and exact description.

My invention relates to a switch indicator, and more particularly to a means for indicating to the engineer of a train the position of the several switches to which he is approaching. It is frequently of advantage to an engineer, in approaching a terminal, to know just what track of the terminal he is coming into and be able to tell ahead of time just what curves and switches he is supposed to take.

An object of my invention is to indicate to the operator, in entering the yard or the limits of the terminal, just what track is open to him.

This and further objects, together with the construction and combination of parts, will be more fully described hereinafter and particularly set forth in the claims.

I attain the above-outlined objects by disposing adjacent the main incoming track a series of lights or other indicators designated in the order in which the terminal tracks are designated, which lights or indicators are adapted to be actuated by the mechanical operation of throwing the switches to complete an electric circuit through the indicator, so that when the switches are thrown to open the way to a particular terminal track, this track will be designated on the indicator.

I have illustrated in the accompanying drawings one mechanical expression of the inventive idea, but it is to be understood that such drawings are illustrative only, and are not designed to define the limits of the invention.

Reference is to be had to the accompanying drawings forming a part of this specification, in which similar characters of reference indicate corresponding parts in all the views, and in which the drawing represents a diagrammatic plan view showing the arrangements of tracks in a terminal, together with the electric circuits controlling the indicating mechanism.

Described more in detail, I have shown a main track A, entering the terminal and leading by suitable switches to terminal

tracks B, designated in the drawings as 1, 2, 3 and 4, and there is also indicated a yard track C. There is also a conventional form of switch-throwing mechanism, 5, 6, 7 and 8, by means of which the several switches are thrown, to make or break the connections between the several tracks.

Leading from any suitable movable part of the switches are switch rods 5', 6', 7' and 8', and in the detailed construction, but one of these switches, as for instance 5 and its connection will be described in detail, it being understood that all of the switches are of substantially the same arrangement comprising a block 15 and a pair of contact members 25 near the opposite ends of the block. The block 15 is always in engagement with one of the pairs of contacts 25, according to the position of the switch, as can be seen from the drawing.

At some convenient place on the main track A, at any preferred distance from the terminal, is positioned the indicator D, in this case shown to be a series of lamps, numbered to correspond to the numbering of the tracks on the terminal, and having one lamp to designate the position of the yard switch. A suitable source of electric energy E is connected to the lamps. Tracing out this circuit, and starting from the battery E, one conductor 32 leads to one of the contacts 25 connected to the switch mechanism 5. From the companion contact 25, a conductor 33 leads to the next adjacent contact 25 connected to the switch mechanism 6, and from its companion contact, a conductor 34 leads to one of the terminals of the indicator designated 4, through the indicator 4 and through the main lamp conductor 35 common to all the lamps, through the return conductor 36 to the battery E. A conductor 37 leads from the conductor 33 to one of the contacts 25 which is connected with the switch mechanism 6. Then the combination contact 25 has a conductor 38 leading to the switch mechanism 7, through this mechanism to the contacts of the switch-actuating means 8, through the circuit 39 back through the lamp 8, conductors 35 and 36, back to the battery E. So it will be understood that throwing any one of the switch mechanisms will simultaneously close a circuit through a suitable connection, and light the corresponding lamp.

As shown in the drawings, it will be noted

that the main track is open to the terminal track 2, so that with the arrangement of circuit-closers, as indicated in Fig. 1, the lamp 2 will be ignited, or the indicator 2 actuated, so as to indicate to the engineer on the main track A that the switches are so set that he has a direct opening to the terminal track B.

As shown in the drawings, the circuit is so formed that when any of the preceding switches throws open the terminal track which it controls, the following switches, and the indicators connected therewith, are cut off, even if the branches are open to the main track.

Having thus described my invention, I claim as new and desire to secure by Letters Patent:—

1. In a railway track indicator,—a series of tracks; a switch controlling each of the tracks; a signal for each track operable by the respective switch; and means associated with each switch and so arranged that when one of the switches is operated it cuts out the signals of the successive tracks.

2. In a railway track indicator,—a series of tracks; a switch controlling each of the tracks; a signal for each track operable by the respective switch; and means associated with each switch and so arranged that when

one of the switches is operated it will cut out the signals of the successive tracks, whether the said tracks are open or closed.

3. In a railway track indicator,—a series of tracks; a switch controlling each of the tracks; a signal for each track operable by the respective switch; and means, including an electric circuit, associated with each switch and so arranged that when one of the switches is operated it cuts out the signals of following tracks, whether the said tracks are open or closed.

4. In a railway track indicator,—a series of tracks; a switch controlling each of the tracks; a signal for each track operable by the respective switch; an electric switch connected to each track switch; and an electric circuit from the electric switch to the signal so arranged that when any of the tracks is opened by its track switch it operates its signal, cutting out the signals of the successive tracks, whether they are open or closed.

In testimony whereof I have signed my name to this specification in the presence of two subscribing witnesses.

CHESTER M. ROE.
